HOLLOW BUILDING BLOCK

Lawrence J. Schoenlein, Baltimore, Md.

Application May 17, 1949, Serial No. 93,747

3 Claims. (Cl. 72—41)

This invention relates to a building block which may be constructed of cement, cinder block or other materials.

The building block of the invention is designed to interlock with adjacent blocks and it is designed primarily to be readily alignable with adjacent blocks in order to make the spacing between the blocks uniform and in order to make the block walls absolutely vertical or plumb. The building block consists primarily of two spaced panels separated and joined together by cross-walls and the cross-walls are so spaced in the block that when the blocks are erected in staggered horizontal rows or in vertical alignment that there will be continuous passages vertically between the cross-walls for the conduits for house facilities that are usually passed through the walls such as plumbing, electricity and gas. The spacing ribs on both panels, resting in contact with ribs on the lower blocks, insure equal mortar distribution and equal load distribution in the wall, and consequently complete stability of the walls. Building blocks have generally been so heavy that they have been difficult to handle and another object of this invention is to place hand holes at the ends of the block so that they may be readily handled. Another object of the invention is to place furring strips on the back of the blocks and to provide the strips with a porous slab or panel which could either be the final inner wall finish or plaster could be applied directly to the slabs. Yet another object of the invention is to provide a block which may have integrally with it such front surface design as may be desired, a brick surface design being illustrated.

Other objects and advantages of the invention will be apparent from the following description and the accompanying drawing forming a part hereof and in which:

Figure 1 is a top plan view of a single block.

Figure 2 is an end elevation of a wall showing several rows of blocks.

Figure 3 is a horizontal sectional view of the vertical joint between two blocks in one row on line 3—3 of Figure 2.

Figure 4 is a similar view on line 4—4 of Figure 2.

Figure 5 is a front elevational view of a wall built of the blocks of this invention.

Figure 6 is a rear elevational view of the same.

Figure 7 is a top plan view of the same.

Figure 8 is a vertical sectional view on line 8—8 of Figure 7.

Figure 9 is an end view of alternate blocks when faced with brick.

In the drawings similar numerals refer to similar parts throughout the several views.

The block is made up of front and rear panels, 1, 2. The front panels as illustrated have preformed thereon a simulation of bricks 3. The panels are connected by spaced crosswalls 4.

Peripherally extending around both front and rear panels are beads or ribs 5 which are preferably placed around the panels near their adjacent faces. The ribs, as shown, on each panel of each block are half as wide as is the desired channel 6 between adjacent blocks. This leaves room for mortar 7 between the cross-walls 4 and the panels, both front and rear as shown at 8. In placing the blocks one upon the other no mortar is placed on the ribs 5 either on the top or ends of the panels prior to the placing of the next block, rather the mortar is placed upon the top of the cross-walls and the top of the panels to the front and back of ribs 5.

2

The adjacent blocks are then aligned with the ribs in exact alignment and in contact with each other and by this guidance exact spacing between blocks is obtained and also exact vertical alignment of the blocks is obtained. The blocks are securely locked together by means of the mortar between the panels and the cross-walls as shown in Figures 2 and 8.

The cross-walls 4 are positioned so that those nearest the end are spaced part way from the ends, and as illustrated they are half the distance from the ends of the blocks as there is space between the respective cross-walls. By this construction when the blocks are laid in rows horizontally and those in the upper row are staggered in relation to those in the lower, the cross-walls 4 of the upper block will fall immediately over half the cross-walls on the two adjacent lower blocks so that a vertical space as shown at 9 goes the whole depth of the wall forming an air space which insulates the wall in the best manner possible and also forming spaces for conduits for household services. Each block has in the cross-wall nearest the end of the block hand holes 10 which have metal inserts 11 placed therein to give the erector a smooth and easy grip upon the block.

The front surfaces of the blocks may have on them any desired pattern. Bricks are shown in the present instance and in order to make the divisions between the blocks as inconspicuous as possible, the bricks are shown on each block with the ends of some bricks coinciding with the ends of the blocks as shown at 12. Since it is, of course, desired to illustrate the bricks as also being staggered, the joint between some blocks will come at the brick center, half being on each adjacent block as shown at 13. In this instance the portion of the channel that would exist between the ends of adjacent blocks, on the front panel, is built up as shown at 14, back of these simulated bricks. It will, of course, be apparent, as shown in the lower row of blocks in Figure 5 that the center brick on adjoining blocks will require a different block end formation, as shown in Figure 9, in which one half of the center brick projects to the end of the block as shown at 15 and in which event the portion of the channel between blocks back of it will be built out as shown at 16 in Figure 9. Although it is desired to make the blocks as nearly uniform as possible, this departure from uniformity is required when bricks form the facing.

The rear of the block has thereon vertically extending furring strips 17. These furring strips are also spaced on the rear of the block so that when adjacent horizontal rows of the blocks are staggered, the furring strips will form a substantially continuous vertical strip, that is, the end strips on one block will be vertically between the strips on the centers of the blocks above and below. It is preferred that the furring strips have on them and formed with them, as well as with the whole block, the slabs 18 which are preferably porous so that the plaster will adhere directly to them, or wall board could be glued to them.

This slab is preferably extended around the edges of the block to coincide with the outward extent of the ribs 5 and the edges are rounded as shown at 19 so that the slabs could form the interior surface of the wall without it being necessary to add other interior finishes thereto.

It will, of course, be apparent that both the bricks 3 and the slab 18 could be formed of the same material as the whole block or they could be formed separately on the block after the block is finished, in which event they could take different formations both of material and color than the base of the block.

The space between the slab and the rear panel of the block is most desirable for the drainage of the moisture of condensation on the interior of the building and to prevent its affecting the inner wall of the building.

It will be apparent that various modifications in the block may be made without departing from the invention as defined in the accompanying claims.

What is claimed as new and is desired to be secured by Letters Patent is:

1. A substantially rectangular building block having

spaced front and rear substantially rectangular panels, mortar receiving edges extending peripherally substantially around each panel at right angles to the panel faces for a substantial portion of the thickness of the panels, a rib extending peripherally outwardly from said edges of both panels at the inside face of each panel flush therewith and in the direction of the planes of the panel faces, each rib having an outer weight sustaining edge normal to the panel face, the configuration of the top and bottom and the ends, respectively, of the panels being identical, ribs on adjacent blocks when the blocks are assembled into a wall, free of mortar on the weight sustaining edges of the ribs, being aligned together to evenly space the blocks and to serve as guides to align the blocks vertically and horizontally, the ribs on adjacent blocks spacing the blocks to form a channel therebetween double the width of the ribs for the receipt of mortar therein and whereby mortar when placed on the edges next to the ribs prevents sidewise displacement of the blocks, a plurality of vertically extending and substantially spacing cross-walls between and attaching said panels together spaced laterally substantially from the adjacent panel side edges, whereby the edge registry of the perimeter of the inner panel faces and ribs with adjacent blocks is readily apparent between the panels, the tops and bottoms of the cross-walls being substantially in the planes of the edges of the tops and bottoms of the panels, said cross-walls being spaced one from the other and being positioned for the receipt of mortar to connect them with the cross-walls of the adjacent upper and lower blocks.

2. The block of claim 1 including integral vertically extending furring strips on the outer face of the rear panel, the strips extending vertically beyond the mortar receiving edges of the rear panel, corresponding in extent to the rib therearound, to form a further sidewise interlock upon placing mortar around the edges.
3. The block of claim 1 including integral vertically extending furring strips on the outer face of the rear panel, said strips being spaced horizontally on the panel to form a substantially continuous vertical strip with strips on vertically adjacent blocks, when two layers of blocks are arranged in staggered relation one upon the other, the strips extending vertically beyond the mortar receiving edges of the rear panel, corresponding in extent to the rib therearound to form a further sidewise interlock upon placing mortar around the edges and a slab extending across the strips on each block, coextensive with the outermost extent of the ribs.
